MEASURING AND DISPENSING INSTRUMENT

Filed April 4, 1924

Patented Nov. 25, 1924.

1,516,942

UNITED STATES PATENT OFFICE.

ERNEST E. WISE, OF OMAHA, NEBRASKA.

MEASURING AND DISPENSING INSTRUMENT.

Application filed April 4, 1924. Serial No. 704,283.

To all whom it may concern:

Be it known that I, ERNEST E. WISE, a citizen of the United States, residing at Omaha, in the county of Douglas and State 5 of Nebraska, have invented certain new and useful Improvements in a Measuring and Dispensing Instrument, of which the following is a specification.

This invention relates to a measuring and 10 dispensing device particularly useful in the practice of dentistry, and has for its object to provide an instrument which will consist of few and simple parts, will be convenient in use and may be readily adjusted for dispensing ingredients in greater or lesser 15 quantities, said ingredients when dispensed being uniform in proportions.

With the foregoing objects in view the invention presents a novel and useful construction, combination and arrangement of parts 20 as described herein and claimed, and as illustrated in the accompanying drawing, it being understood that changes in form, size, proportion and minor details may be made, 25 as found to be of advantage, said changes to be determined by the scope of the invention as claimed.

In the drawing, Fig. 1 is a view of the device in longitudinal section, the plunger being 30 extended. Fig. 2 is a side view of a plunger or carrier. Fig. 3 is a plan view showing the plunger disposed in a tubular casing, and partly in section, the casing being in longitudinal section. Fig. 4 is an end 35 view of a disc, operating as a dial and handle for the plunger. Fig. 5 is a sectional view on line 5—5 of Fig. 3. Fig. 6 is a sectional view on line 6—6 of Fig. 2. Fig. 7 is a broken away sectional view showing the 40 normal position for the plunger within the tubular casing. Fig. 8 is a view partly in longitudinal section to illustrate adjustable features of the invention.

Referring now to the drawing for a more 45 particular description, numeral 9 indicates a tubular casing provided on its upper side with receptacles 10 and 11 each being in communication with the casing, the exit ports for these receptacles being indicated 50 respectively at *a* and *b*.

The plunger 12, in the present instance, 55 consists of apertured blocks or cylindrical sections 13, 14, 15 and 16 and a screw-rod 17, the latter being provided at one of its ends with a disc or handle 18 having indicating characters *c* thereon.

The screw-rod is disposed in the apertures of the cylindrical sections, the sections 15 and 16 being adapted to have a limited longitudinal movement in the casing when the 60 rod 17, by use of the disc, is rotated, parts of said sections 15 and 16 being interiorly threaded to be engaged by the threaded parts *d* and *e* of the screw-rod, as shown in the drawing, and it will be understood that 65 since the screw-rod is provided with detents or collars 19 and 20 which are disposed in the ends of the section 13, said section 13 will be prevented from moving longitudinally of said rod when the latter is rotated, 70 and the section 14 will be prevented from such longitudinal movement since the rod is provided with a detent or collar 21 and a projection 22, said collars 21, 19 and 20 being disposed in the planes of the sections 75 and not operating to prevent a free rotation of said rod.

Numerals 23 and 24 indicate spillways or discharge ports for the casing, the port 24 being comparatively near to the port *b* of 80 the receptacle 11, and the port 23 being comparatively remote from the port *a* of the receptacle 10.

That part indicated at *e* of the screw-rod 85 is finely threaded and the part *d* of said rod is coarsely threaded. Any rotatable movement of the sections or any of them, which otherwise might occur when the screw-rod is rotated, will be prevented since said sections are provided with grooves 25 in which lugs 90 26 of the casing engage. Numeral 27 indicates a spring, its normal retracted position being shown in Fig. 7 of the drawing.

As described, chambers may be formed in the casing, as the chamber 28 between the 95 ends of the sections 13 and 15; and the area and volume of this chamber may be increased or diminished, as likewise may the chamber 29 which is disposed between the ends of the sections 14 and 16, the proportion 100 of these chambers as to volume remaining the same, and an operator may cause, if so desired, the normally adjacent ends of the sections mentioned to move into contact. If it is desired that the volume of the chambers be increased, the disc may be rotated in one direction for that purpose, and a rotation of the disc and screw-rod in an opposite direction will cause a decrease in the volume 105 of the chambers.

As first stated, the instrument is particularly of advantage for the use of dentists 110

when measuring ingredients in the formation of alloys of mercury with certain kinds of metals, the alloy being hard or soft according to the proportion of mercury used; and by use of the device the ingredients will not become wasted, as they often are by assuming and using improper proportions, the use of the device also operating as a saving of time of an operator.

- 10 In operation, the parts being disposed as shown in Fig. 7, the volume of the chambers may be reduced by rotating the screw-rod and its disc, so that said chambers will each contain a limited quantity of the ingredients, 15 the receptacle 11 being adapted to contain mercury and the receptacle 10 being adapted to contain another metal or metals in powdered form, such as silver or the like. The plunger 12 may then be drawn outwardly to 20 permit the chambers 28 and 29 to communicate with the exits *a* and *b* of the respective receptacles 10 and 11, said chamber 29 becoming filled with mercury and the chamber 28 being filled with said other metal or 25 amalgam.

The operator then permits the plunger to slide inwardly of the casing by operation of the spring, the mercury being moved and discharged in the spillway 24 before the amalgam in chamber 28 is discharged in the spillway 23, the ingredients which will be received in the container 30, by the operation described, being of suitable proportions for the reason that the volumes or containing 35 capacity for the chambers 28 and 29 had been predetermined.

It will be understood, of course, that the degree of inclination for the threads of the parts *d* and *e* of the screw-rod 17 will determine the proportion of parts for the alloy, the volumes for the respective chambers 28 and 29 being also arranged, the proportions for the ingredients dispensed being the same whether a large or very limited supply is required. However, it is sometimes desired to add an additional quantity of mercury to the alloy, and since the distance between the port 24 and the port *b* is less than the distance between the port 23 and the port *a*, an additional quantity of mercury may be delivered to the container 30 from the receptacle 11 without the delivery thereto of any of the contents of the receptacle 10, and it will be seen that in such an instance the delivery of 55 such quantity of mercury may be under control of an operator by rotating the screw-rod.

Numeral 31 indicates a constricted part of the hollow standard 32 which communicates with the ports 23 and 24, said part 31 being a matter of convenience to facilitate a delivery of the alloy to the container 30.

Numeral 33 indicates a slot which is formed in a part of the casing, and the plunger is provided with a lug 34 which is adapted to engage in this slot to limit the extent of movement of the plunger outwardly of the casing, the result in operation being that when the plunger is moved outwardly to its farthest extent the chambers 29 and 28 will then be disposed in communication with the respective ports *b* and *a* of the receptacles.

I claim as my invention,—

1. In a measuring and dispensing instrument, a casing provided with intake ports and discharge ports, a plunger slidably mounted in the casing and including blocks, a rotatable screw-rod traversing the plunger and having threaded connections for moving the blocks longitudinally of the plunger to provide chambers in communication with the intake ports of the casing, said plunger being movable to dispose said chambers in communication with the discharge ports of the casing, the threaded connection of the screw-rod with said blocks being such that when the screw-rod is rotated one block will move at a speed greater than another block for changing the relative volumes of said chambers.

2. In a measuring and dispensing instrument, a casing provided with intake ports and discharge ports, a plunger slidably mounted in the casing and including a pair of apertured blocks and adapted to be moved longitudinally of the casing to provide chambers communicating with the intake ports of the casing, resilient means for moving the plunger to dispose the chambers in communication with the discharge ports of the casing, and a screw-rod disposed in the apertures of the blocks, said screw-rod being revoluble for simultaneously moving said blocks at different speeds for causing a change in volume of one chamber as compared with the volume of another chamber.

In testimony whereof, I have affixed my signature in presence of two witnesses.

ERNEST E. WISE.
